UNITED STATES PATENT OFFICE.

MERRILL E. SKINNER, OF WILKINSBURG, PENNSYLVANIA, ASSIGNOR TO WESTINGHOUSE ELECTRIC & MANUFACTURING COMPANY, A CORPORATION OF PENNSYLVANIA.

VENTILATING SYSTEM FOR REACTANCE COILS.

Application filed September 11, 1920. Serial No. 409,545.

To all whom it may concern:

Be it known that I, MERRILL E. SKINNER, a citizen of the United States, and a resident of Wilkinsburg, in the county of Allegheny and State of Pennsylvania, have invented a new and useful Improvement in Ventilating Systems for Reactance Coils, of which the following is a specification.

My invention relates to ventilating devices, and it has particular relation to the ventilation of reactance coils and the like.

One of the objects of my invention is to provide a device of the character described wherein a cooling air current may be so directed and distributed as to come into contact with all of the heated portions of the coils at points where it will have the greatest effect.

Another object of my invention is to provide an arrangement of baffle plates or barriers that may be easily and quickly applied to a reactance coil without materially changing the structure thereof.

With such objects in view, as well as other advantages which may be incident to the use of the improvement, the invention consists in the parts and combinations thereof hereinafter set forth and claimed, with the understanding that the several necessary elements constituting the same may be varied in proportion and arrangement without departing from the nature and scope of the invention.

In order to make the invention more clearly understood, there are shown in the accompanying drawings means for carrying the same into practical effect, without limiting the improvements, in their useful applications, to the particular constructions which, for the purpose of explanation, have been made the subject of illustration.

In the accompanying drawings,

Figure 1 is a vertical longitudinal sectional view through a reactance coil illustrating an embodiment of my invention.

Figure 2 is a plan view, with parts broken away, of the structure illustrated in Figure 1.

Figure 3 is a view similar to Fig. 1 illustrating a modified form of my invention.

Figure 4 is a plan view, with parts broken away, of the structure illustrated in Fig. 3.

Referring to the drawings:

A reactance coil of any preferred construction is shown as comprising a plurality

of concentrically arranged conductors 1, the coils of which are supported and maintained in spaced relation by radially extending groups of superposed retaining members or cleats 2 of insulating material. The coils 1 and retaining members 2 are preferably arranged to form a central chamber or flue 3 and are bound together by means of bolts 4 which extend vertically through each of the groups of superposed cleats 2 and a plate or disk 5 which covers the top of the coil.

The structure is supported by legs or pedestals 6 of insulating material and construction and over an opening 7 in the floor, through which a current of cooling air is forced from a suitable blower or fan, not shown.

Referring to Figures 1 and 2 of the drawings, a cylindrical barrier 8 is so disposed adjacent the bottom of the structure as to surround the legs 7 and extends from the floor to the lower portion of the coil structure and completely encloses the space between the bottom of the coil and the floor.

By this arrangement, all of the air issuing from the opening 7 is directed upwardly through the coils and escapes radially at the sides thereof between the radially extending supporting and retaining members 2. The air is prevented from passing vertically upwardly through the chamber 3 and passing out at the top of the coil structure by means of the plate 5 which deflects the current downwardly and outwardly through the heated coils in a radial direction.

In Figs. 3 and 4, I have shown a modified form of my invention in which the upper end of the chamber 3, only, is closed by the central plate 5'. A cylindrical barrier 8' extends from the floor to the upper extremity of the coil and entirely encloses the same.

By this latter arrangement, the air is directed upwardly through the coils and escapes at the top thereof.

I claim as my invention:

1. A reactance coil comprising a coil, supporting means therefor, a barrier surrounding said supporting means and terminating adjacent to the lower portion of said coil to form an air chamber therebeneath, and a baffle plate disposed at the top of the coil for deflecting an air current through said coil in a radial direction.

2. A reactance coil comprising a coil having a centrally disposed air core and a baffle plate disposed adjacent to the upper portion of said coil for deflecting an air current through said coil in a substantially radial direction.

3. A reactance coil comprising a coil having a centrally disposed air core, and a baffle plate closing the upper portion of said air core for deflecting a current of air in a substantially radial direction between the respective convolutions of said coil.

4. A reactance coil comprising a coil hav-

ing a centrally disposed air core, supporting members for said coil, a barrier surrounding said supporting means to provide an air chamber beneath said coil, and a baffle plate for closing the upper portion of said air core for deflecting a current of air in a substantially radial direction beneath the respective convolutions of said coil.

In testimony whereof, I have hereunto subscribed my name this 30th day of August, 1920.

MERRILL E. SKINNER.
